UNITED STATES PATENT OFFICE.

WILLIAM H. PEPPER AND ALBERT T. L. DAVIS, OF LACONIA, NEW HAMPSHIRE.

DESIGN FOR A PATTERN FOR KNIT FABRIC.

SPECIFICATION forming part of Design No. 25,492, dated May 12, 1896.

Application filed March 6, 1896. Serial No. 582,143. Term of patent 7 years.

To all whom it may concern:

Be it known that we, WILLIAM H. PEPPER and ALBERT T. L. DAVIS, of Laconia, in the county of Belknap and State of New Hampshire, have invented and produced a new and original Design for a Pattern for Knit Fabrics, of which the following is a specification.

Our new and original design for a pattern for knit fabrics is illustrated in the accompanying drawing, which shows a plan view of a knit fabric with the designed pattern applied thereto.

As shown in the drawing, the pattern is composed of diamond-shaped blocks A B, of contrasting shades or colors, the blocks A B being arranged alternately along diagonal lines, or, in other words, the blocks A A being arranged in rows both laterally and longitudinally and the blocks B B being likewise arranged in rows both laterally and longitudinally. Each diamond-shaped block A is composed of longitudinal alternating wales *a b*, of contrasting shades or colors, the wales *a* being the predominating and characteristic ones. Each diamond-shaped block B is com-

posed of lateral stripes *c d*, of contrasting shades or colors, the stripes *c* being of the same shade or color as the wales *a*, and the stripes *d* being of the same shade or color as the wales *b*. The wales *a b* are perpendicular to the stripes *c d*.

The essential feature of the pattern consists of the diagonally-alternating diamond-shaped blocks, one half being composed of parallel wales of contrasting shades or colors, while the other alternating half is composed of parallel stripes of contrasting shades or colors at right angles to the said wales.

We claim as our invention—

The design for a pattern for knit fabrics, as shown and described.

In witness whereof we have hereunto signed our names in the presence of two subscribing witnesses.

WILLIAM H. PEPPER
ALBERT T. L. DAVIS.
